TYPEWRITING MACHINE

William O. Michelsen, Long Island, N. Y., assignor
to Royal Typewriter Company, Inc., New York,
N. Y., a corporation of New York

Original application September 5, 1934, Serial No.
742,787. Divided and this application Decem-
ber 11, 1934, Serial No. 757,044

5 Claims. (Cl. 197—88)

This invention relates to new and useful improvements in typewriting or like machines generally, although more particularly to the carriage escapement mechanism thereof.

5 This application is a division of an application filed by me on Sept. 5, 1934, Serial No. 742,787, for improvements in Typewriting machines.

10 Among the several objects of my invention is to provide an escapement mechanism wherein a quiet action is produced between the escapement pinion and its back dog when the carriage is being moved in the opposite direction.

In the drawing:

15 Figure 1 is a rear elevation, partly in section, of an escapement mechanism constructed in accordance with my invention;

Figure 2 is a perspective view of the wiper cam and its support;

20 Figure 3 is an enlarged sectional view taken on the line 3—3 of Figure 1; and

Figure 4 is a perspective view of a modified form of cam.

25 In the accompanying drawing, 5 indicates the usual rack which is attached to the carriage, and supported on the main frame of the machine below the rack is a frame A for supporting the escapement mechanism. The frame A includes two spaced horizontal arms 6, 6 and an upwardly extending vertical arm (not shown) in which is journaled a shaft 8 on which is rotatable a pinion 9 having teeth 10 for engaging the rack 5. Fixed to the shaft 8 is an escapement wheel 11 having teeth 12. A back dog 13 for the pinion 9 is pivoted as at 14 to the escapement wheel 11, and a spring B is employed to yieldably retain this back dog in engagement with the teeth 10 of the pinion 9.

30 The escapement wheel 11 is intermittently released during the step by step feeding movement of the carriage by the following noise-reducing mechanism: Pivoted on the horizontal arms 6, 6 of the escapement supporting frame A as at 21, 21 is a dog rocker C which carries a fixed dog 22 and a pivoted or limber dog 23 which intermittently engage the teeth 12 of the escapement wheel in the usual manner whenever the dog rocker C is rocked by the key levers. Rigidly connected to a bracket 24 which is fixed to the rocker C at one side of the pivoted dog 23 is an upwardly projecting vertical arm 25. A flexible U-shaped support 26 has one leg 27 rigidly connected to the lower end of the arm 25 by screws 28, and extending laterally from the upper end of the other leg 29 towards the pivoted dog 23 is an arm 30 to which a wiper cam

31 is pivoted as at 32. This cam is provided with a rock arm 33 to which is connected the upper end of a coil spring 34, the lower end of the spring being anchored to an ear 35 formed on the bracket 24. By means of this construction the cam is yieldingly held in constant wiping engagement with the pivoted dog 23, and functions to normally urge and rock said dog against a stop 36 fixed to the rocker C. The stop 36 is preferably provided with a sound deadening pad 37 for receiving the pivoted dog 23 each time the latter is released from the escapement wheel 11 upon movement of the rocker C. An adjusting screw 38, which is threadably engaged in the upper end of the arm 25, bears against the upper end of the spring leg 29 of the cam support 26 and functions to vary the lateral position of the cam and thereby regulate the amount of movement of the escapement wheel.

35 In operation, assuming the parts to be in their normal positions, as viewed in Figure 1, the rocker C is rocked upon depression of a key lever and the pivoted dog 23 is thereby released from the tooth of the escapement wheel. The escapement wheel is then rotated by the carriage spring until said released tooth engages the fixed dog 22, and simultaneously the pivoted dog is swung against the stop pad 37 by means of the wiper cam 31 and spring 34. The rocker C is then returned to its initial position by the usual return spring, and the pivoted dog is thereby carried into the path of the next tooth of the escapement wheel, the latter being free to turn the pivoted dog 23 to its normal or starting position. Thus, instead of the dog's snapping against a fixed stop as in machines of prior constructions, the dog will be eased into its state of rest by reason of its wiping contact with the cam 31. Any noise which might be occasioned during the return movement of the pivoted dog 23 by reason of the latter contacting the wiper cam 31 will be absorbed by the spring leg 29 of the cam support 26. In Figure 4 I have illustrated a modified form of wiper cam 31a which is provided with a longitudinal slot 38 forming a resultant yieldable cam finger 40 which functions to absorb and thereby reduce any noise which might be occasioned by contact between the pivoted dog 23 and the wiper cam 31 in either of the pivoted movements of the dog.

50 I claim:

1. In a typewriting or like machine, an escapement mechanism including an escapement wheel, a dog rocker, a fixed dog and a movable dog mounted on the rocker and alternately movable into engagement with the teeth of the wheel, a

55

support mounted on the rocker for adjustments towards and from the movable dog, a wiper cam pivoted on the support and contacting the movable dog, and a spring connecting the cam and the rocker for holding the cam in yielding contact with the pivoted dog.

2. In a typewriting or like machine, an escapement mechanism including an escapement wheel, a dog rocker, a fixed dog and a movable dog

10 mounted on the rocker and alternately movable into engagement with the teeth of the wheel, a spring arm mounted on the rocker, a wiper cam pivoted on the spring arm and contacting the movable dog, and yieldable means connecting the

15 cam and the rocker for holding the cam in yielding contact with the pivoted dog.

3. In a typewriting or like machine, an escapement mechanism including an escapement wheel, a dog rocker, a fixed dog and a movable dog

20 mounted on the rocker and alternately movable into engagement with the teeth of the wheel, a spring arm mounted on the rocker, a wiper cam pivoted on the spring arm and contacting the movable dog, yieldable means connecting the

25 cam and the rocker for holding the cam in yielding contact with the pivoted dog, and an adjusting screw mounted on the rocker and engaging the spring arm for varying the lateral position of the cam pivot relative to the movable dog.

30 4. In a typewriting or like machine, an escape-

ment mechanism including an escapement wheel, a dog rocker, a fixed dog and a movable dog mounted on the rocker and alternately movable into engagement with the teeth of the wheel, a vertically disposed bracket arm fixed to the rocker, a U-shaped spring support having one leg fixed to the bracket arm, the other leg terminating in a laterally extending arm, a wiper cam pivoted on said arm and contacting the movable dog, and yieldable means connecting the cam and the 10 rocker for holding the cam in yielding contact with the pivoted dog.

5. In a typewriting or like machine, an escapement mechanism including an escapement wheel, a dog rocker, a fixed dog and a movable dog 15 mounted on the rocker and alternately movable into engagement with the teeth of the wheel, a vertically disposed bracket arm fixed to the rocker, a U-shaped spring support having one leg fixed to the bracket arm, the other leg terminating in a laterally extending arm, a wiper cam pivoted on said arm and contacting the movable dog, yieldable means connecting the cam and the 20 rocker for holding the cam in yielding contact with the pivoted dog, and an adjusting screw 25 threadably mounted in the upper end of the vertical arm and engaging the upper end of the spring support for varying the lateral position of the cam pivot relative to the movable dog.

WILLIAM O. MICHELS
